[57] CLAIM

The ornamental design for bookrest pillow, as shown and described.

DESCRIPTION

FIG. 1 is a perspective view of a bookrest pillow, showing our new design; the broken line showing of the open book is for environmental purposes only and forms no part of the claimed design;

FIG. 2 is a left side elevational view thereof;

FIG. 3 is a right side elevational view thereof;

FIG. 4 is a front elevational view thereof;

FIG. 5 is a back view thereof;

FIG. 6 is a top view thereof;

FIG. 7 is a bottom view thereof;

FIG. 8 is a perspective view of a bookrest pillow, showing an alternate embodiment of our new design;

FIG. 9 is a left side elevational view thereof;

FIG. 10 is a right side elevational view thereof;

FIG. 11 is a front elevational view thereof;

FIG. 12 is a back view thereof;

FIG. 13 is a top view thereof; and,

FIG. 14 is a bottom view thereof.
